UNITED STATES PATENT OFFICE.

CHARLES MAGEE, OF BROOKLYN, N. Y., ASSIGNOR TO BIGELOW CARPET COMPANY, OF CLINTON, MASS.

DESIGN FOR CARPETS.

SPECIFICATION forming part of Design No. 12,195, dated March 22, 1881.

Application filed February 15, 1881. Term of patent 3½ years.

To all whom it may concern:

Be it known that I, CHARLES MAGEE, of the city of Brooklyn, county of Kings, and State of New York, have invented a new and 5 original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

H is a group composed of the figure f, consisting of a cluster of oval leaves with a circular flower projecting therefrom; also, of the figure j, a stem bearing leaves and flowers, and projecting from the figure f; also, of the figure h, resembling the branch of a tree.

20 I is a figure composed of leaves, from which project slender vines.

F is a figure composed of a cluster of leaves, from which project on slender stems flowers resembling poppies, and also a vine-like spray, g.

25 D is a figure composed of circular, widely-open flowers surrounded by leaves and projecting vines.

The figures described are placed on a regular-patterned background, somewhat resembling fish-scales.
